UNITED STATES PATENT OFFICE.

JAMES R. FLEMING, OF SCRANTON, PENNSYLVANIA.

MINE-CAR-DOOR LATCH-PLATE.

1,116,258.

Specification of Letters Patent.

Patented Nov. 3, 1914.

Application filed December 13, 1913. Serial No. 806,426.

To all whom it may concern:

Be it known that I, JAMES R. FLEMING, a citizen of the United States, and a resident of Scranton, in the county of Lackawanna and State of Pennsylvania, have invented a new and Improved Mine-Car-Door Latch-Plate, of which the following is a full, clear, and exact description.

Among the principal objects which the present invention has in view are: to protect the wooden frame forming the door opening; to provide reversible latches; and to simplify and cheapen the construction of cars of the character named.

In the drawings: Figure 1 is an end view of a car having latch plates constructed and arranged in accordance with the present invention; Fig. 2 is a top view of a latch plate constructed and arranged in accordance with the present invention, showing in connection therewith a section of a corner fragment of a car and of the locking latch for the door thereof; Fig. 3 is a side view of the latch-plate, showing a corner fragment 25 of the car and of the latch for holding the door thereof; Fig. 4 is a perspective view, on an enlarged scale, of the latch-plate.

As shown in the drawings, cars of the character mentioned are provided with sides 30 constructed from heavy wooden timbers 9. The timbers 9 are suitably bolted to metal side framing members 10, which in turn are secured to brackets 11, at the upper ends whereof are formed suitable bearings for a 35 hinge shaft 12. The timbers 9 form the opening for a door 13, which door fits between the ends of said timbers. The blank forming the door 13 is bolted to hinge straps 14.

On the center hinge strap 14, latch arms 15 are pivoted. These arms are guided in a central loop 16 and two side loops 17. Said loops are constructed from metal, and are of conventional shape. The ends of the 45 latch arms 15 rest in recesses 18 of latch plates 19.

The latch plates 19 are each provided with a base plate 20 and a standing plate, the edges 21 whereof are inclined, as seen best in Fig. 4 of the drawings. Reinforcing webs 22 connect the base plate 20 and the standing plate. The base plate 20 is furnished with bolt holes 23 to receive bolts 24 when the plates are secured in service position. The latch plates 19 are mounted on 50 the side sills 25 of the car, in such manner that the inner wall of the recess 18 is flush with the edge of the wooden timbers 9 of the car body. When, in the operation of the car, the attendant at the dumping station strikes the latch arms 15, to lift the same out of engagement with the plate 19, the blow is received upon the walls of the recesses 18, and the wear of the timbers 9 above referred to, is avoided. It will be 55 observed that because of the shape of the plates 19, whereby the recesses 18 are provided with a wall at both sides thereof, said plates may be reversed or interchanged at will. 70

Claim.

In combination, a body having sides formed from boards, the ends whereof are exposed; a door pivoted to swing between the ends of said boards to rest flush therewith when closed; a plurality of latch arms pivoted on said door to overhang said sides; a plurality of latch-plates for said arms, each of said plates having a base, supporting webs and a top opening socket recess, 80 said recess having front and rear walls; and means engaging said base for holding said plate on said body with the rear wall of the socket of said plates flush with the edges of said sides. 85

In testimony whereof I have signed my name to this specification in the presence of two subscribing witnesses.

JAMES R. FLEMING.
